UNITED STATES PATENT OFFICE

ALBERT SÉROR, OF CHICAGO, ILLINOIS

DESIGN FOR A TOY ANIMAL

Application filed November 6, 1930. Serial No. 37,574. Term of patent 7 years.

To all whom it may concern:

Be it known that I, ALBERT SÉROR, a citizen of the United States, and a resident of Chicago, in the county of Cook and State of Illinois, have invented a new, original, and ornamental Design for a Toy Animal, of which the following is a specification, reference being had to the accompanying drawing, forming part thereof.

The figure is a perspective view of a toy animal, showing my new design.

I claim:

The ornamental design for a toy animal, substantially as shown.

In witness that I claim the foregoing as my invention, I have hereunto affixed my signature this 24th day of October, 1930.

ALBERT SÉROR.
